CLAIM

The ornamental design for a cosmetic bottle, as shown.

DESCRIPTION

FIG. 1 is a top, front, right side perspective view of our new design for a cosmetic bottle;

FIG. 2 is a front elevation view of the cosmetic bottle shown in FIG. 1;

FIG. 3 is a right side elevation view of the cosmetic bottle shown in FIG. 1;

FIG. 4 is a rear elevation view of the cosmetic bottle of FIG. 1;

FIG. 5 is top plan view of the cosmetic bottle of FIG. 1; and

FIG. 6 is a bottom plan view of the cosmetic bottle of FIG. 1.

FIG. 7 is a cross-sectional view of the cosmetic bottle taken through line FIG. 7-FIG. 7 of FIG. 3;

FIG. 8 is a cross-sectional view of the cosmetic bottle taken through line FIG. 8-FIG. 8 of FIG. 3; and,

FIG. 9 is a cross-sectional view of the cosmetic bottle taken through line FIG. 9-FIG. 9 of FIG. 3.
